CLAIM

The ornamental design for a pair of football-style cowboy boots, as shown and described.

DESCRIPTION

FIG. 1 is a perspective view of pair of football-style cowboy boots showing my new design; and,

FIG. 2 through 7 comprise a series of engineering views of the left boot of FIG. 1, the right boot being a mirror opposite thereof, wherein:

FIG. 2 is a side elevational view of the medial side thereof,
FIG. 3 is a side elevational view of the lateral side thereof,
FIG. 4 is a front elevational view thereof,
FIG. 5 is a rear elevational view thereof,
FIG. 6 is a top plan view thereof; and,
FIG. 7 is a bottom plan view thereof.
